DRAFT GEAR

Original Filed July 9, 1927

UNITED STATES PATENT OFFICE

HERBERT E. TUCKER, OF SOUTH BEND, INDIANA, ASSIGNOR TO UNIVERSAL DRAFT GEAR ATTACHMENT CO., A CORPORATION OF ILLINOIS

DRAFT GEAR

Original application filed July 9, 1927, Serial No. 204,618. Divided and this application filed July 13, 1928. Serial No. 292,468.

The invention relates to draft gears for railway cars of the type in which intercalated friction plates are employed, and more specifically to gears of this type in which the friction and cooperating elements are mainly housed within the open end of a chambered follower or casing, and this application is a division of my application, Serial No. 204,618, filed July 9, 1927.

In the accompanying drawings illustrating a preferred form of the embodiment of the invention,

Fig. 1 is a detail, central, vertical, longitudinal section through the gear, the parts being shown in released position; and

Figs. 2 and 3 are details of various of the gear elements.

The forward or open end portion of a chambered follower or casing is shown at 10.

This casing is of common construction, and it will be understood that its rearward end, not shown, is as usual closed by a plate which may be either integral or separate from the remaining portion. The opposing follower 11 is shown as a plate. The two followers will be enclosed within a suitable form of yoke, not shown.

The friction plates are arranged in two groups, each group cooperating with the wall of the casing 10 which walls may constitute the top and bottom of the casing, or its sides. Each group of friction plates is composed of one or more relatively short plates 12 having lateral lugs 13 for interlocking with ribs as 14 formed across the inner faces of the walls of the casing which connect the walls against which the plates are seated; and a set of relatively longer plates, one or more in number, as 126, which are not interlocked with the casing but are free to move longitudinally relatively thereto, being restrained only by their frictional engagement with other parts of the gear. Both sets of plates are free to move transversely of the gear in a direction normal to their flat faces. Plates 126 normally project beyond the open end of the casing 10 to within a short distance of the plate 11. At least one plate of each group, as 15, is tapered toward its outer end.

A pusher element 138 is seated against the

plate 11 and may, as shown, be square in cross section having a stem as 137 projecting centrally from its inner face into the casing 10, this stem having parallel side faces.

Seated against the inner plate of each group is a friction shoe 125 having on its inner face adjacent each end a wedging surface as 127, 128, the former being inclined forwardly, that is toward the inner end of the casing 10, and outwardly, thus away from the axis of the gear, the latter being inclined in the opposite direction.

Seated against each of the parallel faces of the stem 137 is a shoe 131 having adjacent each of its ends wedging faces 129, 133, both of which are inclined forwardly and outwardly, the former having the same inclination as and bearing upon the wedging surface 127 of the shoe 125.

A pair of triangular wedge blocks 134 are seated upon the shoulders 136 which constitute the inner face of the element 138, one at each side of the stem 137, their apexes extending into the space between the elements 125 and 131, their inclined faces 135 and 132 cooperating with the faces 128 and 133 thereof. The wedge faces 128 and 135 are more acute than the other wedging faces, the latter being of substantially uniform pitch.

The elements 131 extend inwardly beyond the end of the stem 137 and are at all times in engagement with a plate 16 which forms a seat for a set of helical springs 142, the opposite ends of which seat against the closed end of the casing 10.

There is shown a retaining bar 139 as extending through a pocket in the stem 137 for holding the parts in assembled relation prior to the installation of the gear, the bar 139 being held against longitudinal displacement by means of a ball 141 seated in a recess 142 in the bar and held in place by a spring 17 reacting against the plate 18 closing the end of the pocket in the stem. This retaining element is not claimed as a part of the invention.

Normally the parts assume the positions shown in Fig. 1, the inner ends of the elements 131 and the plates 126 being in engagement with the spring seat 16 and the outer

ends of these plates being adjacent to but out of contact with the follower plate 11. Upon compression of the gear in buff, the follower 11 moves backwardly carrying with it the thrust element 138 and the wedge blocks 134. 5 The elements 131 are also moved backwardly because of the blunt angle of their engaging faces with the blocks 134, carrying backwardly the spring seat 16 against the resistance of 10 the springs 142 and moving it away from the inner ends of the plates 126.

Because of the more acute angle of the co-operating wedging faces of the blocks 134 and the shoes 125, the latter tend to lag, and compressive force is applied to the friction 15 plates, the elements 125, however, being urged forwardly by the wedging action, their inner ends being maintained in engagement with the inner ends of the elements 131. The 20 spring seat 16 is carried away from the plates 126. When the follower plate 11 comes in contact with the plates 126, they are forced back between the shorter friction plates and as the closing of the gear continues, the pressure upon the two groups of friction plates 25 is augmented because of the tapered form of the plates 15.

Upon release, the springs move backwardly the elements 131 and 125, the release being 30 facilitated by the tapering form of the plates 15 and when the spring seat again comes into engagement with the plates 126, they are restored to normal position.

The operation of the gear in draft is the 35 same except in a reverse direction.

As the parts become worn, due to the frictional engagement of the plates, the elements 131 are moved outwardly sufficiently to take up all of the slack without materially reducing the tension of the springs. 40

I claim as my invention:

1. In a draft gear in combination, a chambered follower, an opposed plate follower, two groups of intercalated friction plates housed within the chambered follower, one set of each group being anchored against longitudinal movement and the other set being floating and normally projecting from the chamber, one plate of each group being tapered towards its outer end, a pair of friction shoes bearing respectively upon the inner plate of each group, such shoes having oppositely inclined wedging faces, a pusher element seated against the plate follower and 45 having a pair of forwardly facing shoulders and a stem projecting forwardly from such shoulders and having parallel side walls, a wedge plate seated against each of such walls and having forwardly and outwardly inclined faces at each end, the face at its inner end cooperating with the wedge face at the inner end of the adjacent shoe, a block seated 50 on each shoulder and having wedging faces cooperating with the wedges at the outer ends 55 of the adjacent shoe and wedge plate, a spring 60

seat engaging the inner ends of the wedge plates and engageable with the floating plates, and springs reacting between such seat and the end wall of the chambered follower.

2. In a draft gear in combination, a casing, 70 an opposed follower, two groups of intercalated friction plates within the casing, a thrust element seated against the named follower and having forwardly facing shoulders and a forwardly projecting stem having parallel sides, friction wedge shoes engaging 75 the plates, triangular wedge blocks, seated on the shoulders of the thrust member and engaging wedging faces of the shoes, a plate seated against each of the named faces of the stem and having spreading wedging faces 80 cooperating with the shoes and wedge blocks, and spring means resisting the advance of the plates and for restoring the gear elements to normal position upon release. 85

In testimony whereof I affix my signature.

HERBERT E. TUCKER.
